UNITED STATES PATENT OFFICE.

HUBERT LANG, OF CHICAGO, ILLINOIS, ASSIGNOR TO THE GOSS PRINTING PRESS COMPANY, OF CHICAGO, ILLINOIS, A CORPORATION OF ILLINOIS.

SHEET-GRIPPING DEVICE FOR PRINTING-PRESSES.

1,108,193.

Specification of Letters Patent. Patented Aug. 25, 1914.

Application filed May 31, 1913. Serial No. 770,965.

To all whom it may concern:

Be it known that I, HUBERT LANG, a citizen of the United States, residing at Chicago, in the county of Cook, in the State of Illinois, have invented certain new and useful Improvements in Sheet-Gripping Devices for Printing-PresSES, of which the following is a specification, reference being had to the accompanying drawings.

10 This invention relates to sheet gripping devices for printing presses.

Heretofore in some constructions the gripping devices, which carry a sheet or a bunch of sheets around on the surface of a cylinder by pressing their lead edges against the cylinder, have been closed by means of a lever provided with a stud or roller working on a suitable cam, such closing being accomplished against the action 20 of a spring which automatically opens the gripper when the roller passes off of the high portion of the cam. In this construction no adequate provision has been made for varying the throw of the gripping devices in closing to suit different thicknesses 25 of paper, different numbers of sheets to be gripped or other varying conditions. Moreover, inasmuch as the closing of the gripper effected by the cam has been against the action of the spring by which the gripper is adapted to be closed, there has been a very considerable wear upon the cam and upon the roller.

30 It is one of the objects of my invention to provide a construction in which the gripper is closed through the medium of a positive movement of the operative member, in which the extent of the throw of the gripper may be varied.

40 It is another object to provide in a construction of this sort means for mounting the gripper device yieldingly relative to the positively actuated member by which it is closed.

45 It is another object to provide a construction comprising a cam for closing the gripper in which the closing action shall not be against the action of a spring by which the gripper is adapted to be opened, by which 50 improved construction the wear upon the cam shall be materially decreased.

It is another object of my invention to improve devices of this sort in sundry details hereinafter pointed out.

55 The means by which I have accomplished

these objects are illustrated in the accompanying drawings and are hereinafter specifically described.

That which I believe to be new is set forth in the claims.

In the drawings,—Figure 1 is an end view of a cylinder provided with my improvements, the main portion of the operating cam being shown only diagrammatically in order to be able to show the parts beyond in full lines; Fig. 2 is a view of the cylinder shown in Fig. 1 as seen from the left in Fig. 1; Fig. 3 is a view similar to Fig. 1 illustrating a different phase of the operation of the cylinder; and Fig. 4 is an enlarged detail showing the manner in which the grippers are mounted upon the gripper shaft.

Referring to the several figures of the drawings in which corresponding parts are indicated by the same reference characters—10 indicates a cylinder, which may be either the rotary carrier of a rotary folding machine or may be a collecting cylinder of any well-known type, or may be a gripper cylinder of any well-known form. 11 indicates the shaft upon which said cylinder is mounted, said shaft being supported in any suitable framework not shown. 12 indicates a gripper shaft revolvably mounted in said cylinder near its outer periphery, said shaft 12 having fixed upon it at suitable intervals therealong a plurality of grippers 13 mounted upon said shaft in suitable recesses 14 in the surface of the cylinder. As best shown in Fig. 4 the grippers 13 are secured by means of suitable screws upon split collars 15 which are clamped by means of screws 16 upon the shaft 12. As also shown in said Fig. 4 the outer ends of the grippers 13 are adapted to be brought down squarely upon the edge of the sheet of paper or of a bunch of sheets of paper lying upon the surface of the cylinder 10, such sheet or sheets being indicated in Figs. 1 and 4 by the numeral 17.

Coming now to the means for rocking the gripper shaft 12, 18 indicates a lever secured by means of a key 19 upon the outer end of the shaft 12.

20 indicates a rod pivotally secured by means of a screw 21 to the end of the lever 18.

22 indicates a lever pivotally mounted upon a stub-shaft 23 carried by the cylinder.

24 indicates a swivel-eye mounted on one end of the lever 22, through which the rod 20 passes, a spring 25 being mounted on said rod between the swivel-eye 24 and a collar 26 which is secured by means of a set-screw 27 adjustably upon said rod. 28 indicates nuts screw-threaded upon the end of the rod 20 beyond the swivel-eye 24. 29 indicates a rod pivotally mounted to the opposite end of the lever 22.

30 indicates a link one end of which is revolvably mounted upon the shaft 12 and the other end of which is pivotally connected to the free end of the rod 29 by means 15 of a bolt 31. Mounted upon the free end of the link or lever 30 is a stud 32, in the construction shown being in the form of a roller revolvble upon the bolt 31.

33 indicates a cam member (shown largely 20 diagrammatically in the figure) provided with a bracket 34 by which it is mounted upon the framework of the machine in any suitable manner (not shown) the bracket 34 being provided with an arc-shaped slot 35 25 by which connection is to be made with the framework whereby the cam member can be given a partial rotation relative to the frame. As best shown in Figs. 1 and 3, the cam member 33 is provided with a cam 30 groove 36 in which said roller 32 operates, the greater portion of said cam groove being concentric about the axis of rotation of the cylinder, but a portion thereof being a moderate, easy digression from circular form.

35 It will be readily understood that with the cylinder 10 rotating in clockwise direction in the figures, for the greater part of the rotation the roller 32 will operate in the circular part of the cam groove 36, whereby 40 the lever 22 is held in the position shown in Fig. 1, serving through the medium of the spring 25 to hold the lever 18 in the position there shown with the gripper 13 pressed yieldingly against the sheet or 45 bundle of sheets 17 upon the cylinder. It will be understood that the pressure of the spring 25 upon the gripper 13 can be regulated by the adjustment of the collar 26 through the medium of the set-screw 27. 50 When, however, the roller 32 is brought into engagement with the rise of the cam groove 36 the lever 22 is turned in a clockwise direction in Figs. 1 and 3. The first result of a turning of the lever 22 in a clockwise direction is the expansion of the spring 25 until the swivel-eye 24 is brought into contact with the nuts 28, whereupon by a further movement of the lever 22 in clockwise direction the lever 18 is also given a rotation 55 in the same direction releasing the grippers 13 from the paper 17 and opening the grippers finally to such a position as that shown in Fig. 3. Upon the still further rotation of the cylinder, the roller 32 is, of course, 60 brought back to the concentric portion of

the groove 36 turning the lever 22 in counter-clockwise direction. The lever 18 is moved by this action in the same direction through the spring 25 until just at the end of the movement of the lever 22 the grippers 13 are 70 brought into engagement with the paper 17 on the cylinder, whereupon the final movement of the lever 22 is against the action of the spring 25.

What I claim as my invention and desire 75 to secure by Letters Patent is,—

1. The combination of a cylinder, a gripper-shaft revolvably mounted thereon, a plurality of grippers fixed on said shaft, and positively-actuated means connected to said 80 shaft for rotating it for opening and closing said grippers, the connections between said positively-actuated means and said shaft comprising yielding means adapted to be moved bodily by the operative movement of 85 the actuating means, said yielding means being adapted to be stressed only at approximately the end of the operative closing stroke of said actuating means.

2. The combination of a cylinder, a gripper-shaft revolvably mounted thereon, a plurality of grippers fixed on said shaft, a cam member provided with a cam groove, a stud 90 adapted to be actuated positively by movement along said cam groove, and connections 95 between said stud and said shaft whereby the movement of said stud along said cam groove serves to rock said shaft for opening and closing said grippers, said connection comprising yielding means adapted to be 100 moved bodily by the operative movement of said stud, said yielding means being adapted to be stressed so as to exert a yielding pressure upon said cam only at approximately 105 the limit of the operative closing stroke of said stud.

3. The combination of a cylinder, a gripper shaft revolvably mounted thereon, a plurality of grippers fixed on said shaft, a lever connected with said gripper shaft for 110 rocking it for opening and closing said grippers, and a cam-member provided with a cam-groove for operating said lever positively for both opening and closing said 115 grippers, the connections between said gripper shaft and said lever comprising yielding means adapted to be moved bodily by the operative movement of said lever and adapted to cause said grippers to close upon the complete closing movement of said lever, the compression of said yielding means caused by the closing movement of the lever being controlled by the thickness of the matter gripped.

4. The combination of a cylinder, a gripper shaft revolvably mounted thereon, a plurality of grippers fixed on said shaft, a lever connected with said gripper shaft for 120 rocking it for opening and closing said grippers, and a cam-member provided with a 125

groove in which said roller runs for positively operating said lever for both opening and closing said grippers, the connections between said gripper shaft and said lever comprising yielding means adapted to be moved bodily by the operative movement of said lever and adapted to cause said lever to close upon the complete closing movement

of said lever, the compression of said spring caused by the closing movement of the lever 10 being controlled by the thickness of the matter gripped.

HUBERT LANG.
